NEWSPAPER TYPE CHASE

Clifford W. LeGate, Edmond, Okla.

Application February 15, 1954, Serial No. 410,251

2 Claims. (Cl. 101—394)

The present invention relates to the art of newspaper publication, and more particularly to the registration of color printing plates or casts used on rotary cylinders of a newspaper printing press.

It is well known to those skilled in the art that a separate cut or printing plate must be used to print each color of a colored picture being reproduced including black, if black is used. Each one of the several casts or plates must be lined-up or registered on the press in order that the picture will be properly printed. This registration is not too difficult a task on a flat-bed or letter-press where the cut can be comparatively easily moved, but when color is to be reproduced on a newspaper rotary press, considerable difficulty is often encountered because the circular printing plates cannot be moved as easily and in many cases not far enough to effect a register with the other mating color plates, or casts.

In newspaper work human error as well as mechanical failure may easily enter into the making of out-of-register stereotype casts or plates. The several matrices rolled from the properly composed type chases may not shrink evenly or alike; the operator may make an uneven trim on the edge of the matrix; the matrix may not be placed properly within the stereotype casting machine, resulting in a stereotype cast with the image twisted or out of line with its longitudinal direction of roll. Any one of these and other factors may cause the plates to be out-of-register when placed upon the printing cylinders. This out-of-register will not be detected until the presses have been started and a number of papers printed. Some adjustment may then be made, as stated hereinabove, which amounts to approximately a total of thirty thousandths of an inch of movement from top to bottom with respect to the page being printed. It is necessary to stop the presses each time such an adjustment is made. If this adjustment is not sufficient to get the plates in register, the plates must be made over, or run as they are, which is usually the case in newspaper work because time schedules will not permit the remaking of the plates.

One method for effecting better registry of the plates has been devised in the scoring or placing of grooves along the four sides of the type chase which makes a raised line on the matrix by which the stereotype operator trims the matrix. This helps in the registering of the plates, but human error in trimming all matrices alike is most prevalent at this stage of the operation.

Another improvement has been the use of thermostatically controlled heat in the vacuum operated matrix shrinking machines. Theoretically all matrices should shrink alike, but some matrices contain more moisture than others and consequently do not shrink alike. This variation in shrinkage is so slight that it will not be detected until the presses start printing.

The results attained by my invention has been sought for a long time, but has never been attained.

The present invention overcomes the above defects in producing registered rotary color plates by providing

2

a means of accurately checking the size of the matrix and the printing plates, or casts.

5 The principal object of the present invention is to provide register marks for checking the register of rotary color plates at any stage during the process of their manufacture.

Another object is to provide register marks on the newspaper type chases that are in a fixed position and do not have to be "lined up" for registry.

10 Another object is to provide a means of trimming the edges of the matrix while they are held in registering position.

Still another object is to provide a means for checking the variation of shrinkage, if any, of the several matrices.

15 Yet another object is to provide a means for identically registering each printing plate for the final milling operation which cuts the gripping "pockets" therein.

20 The present invention attains these several objects by providing register marks upon the type chases used in the page "make-up" which are transmitted to the matrix when molded. A vacuum operated trim table holds the finished matrix in register by the register marks while three sides of the matrix is trimmed to size. This vacuum table may be used to further check the register of the 25 various matrices after the matrices have been heated for shrinking. During the stereotyping operation the matrix transfers the register marks to the stereotype cast or printing plate. A plate checking device is provided to check the register of each plate and identically position each 30 plate for drilling additional register holes which act to register each plate during the last stage of the milling operation.

35 Other objects will be apparent from the following description when taken in conjunction with the accompanying three sheets of drawings, wherein:

Figure 1 is a plan view of a conventional type chase used in newspaper work;

Figure 2 is a horizontal cross-sectional view taken substantially along lines 2—2 of Fig. 1;

40 Figure 3 is a horizontal cross-sectional view taken substantially along line 3—3 of Fig. 1;

Figure 21 is a fragmentary cross-sectional view of another embodiment of a part of the invention.

Like characters of reference designate like parts in those figures of the drawings in which they occur.

In the drawings:

Make-up

Reference numeral 1 indicates, as a whole, a conventional newspaper type chase having a top end 2, a bottom end 3 and right and left sides 4 and 5, respectively. These side designations have reference to the make-up of the newspaper page to be printed therefrom. The type chase 1 has a conventional lock-up bar 6, adjacent the bottom end 3, and lock-up bar 7 adjacent the left side 5, and a type or engraving space area as indicated by the numeral 8. The type chase 1 has conventional trim grooves in the top surface of its ends 2 and 3 and lock-up bars 6 and 7, as indicated by the lines 10 in Fig. 1, and as shown more clearly in Fig. 4. As shown in Fig. 4, the groove 10 is located adjacent but outwardly from the shoulder 11, along the type side of the type chase 1.

The above description discloses a conventional newspaper type chase upon which my device is proposed to be installed.

It is conventional practice in printing color work to place a register mark upon the vertical and horizontal center lines of the picture or working drawings before making engravings therefrom. These marks are used in lining up the "cut" when the different colors are being printed, and after completion of the printing, the printed register marks are trimmed off of the printed product. It is not practical to use such register marks in newspaper printing where the newspapers are printed from a rotary press using a continuous roll of paper stock, because the marks cannot easily be trimmed off and the rotary plates cannot be moved sufficiently to affect a register as explained hereinabove.

In order to place the invention into operation, the vertical and horizontal center lines of the type area 8 of the type chase 1, are located as indicated by the reference numerals 15 and 16, respectively. A register mark 17 is then placed upon the side 4 and end 2, inside of the groove 10. Since the lock-up bars 6 and 7 are movable and do not assume the identical position in lock-up each time a chase is made up, due to the variation in the thickness of metal used in the make-up of a page within the chase, it is necessary to provide a means of locating the register marks on the bottom 3 and the side 5 in such manner that they will be rigidly positioned. This is done, as shown in Fig. 2, by cutting a slot in the top of the end 3 and the side 5 to receive a rectangular plate 18 which is rigidly attached to the end 3 and the side 5 by screws 19, having one end parallel with the outer edge of the chase 1 and the opposite end extending inwardly toward the type area 8 substantially equidistant with the lock-up bars 6 and 7, respectively, when in "make-up" position. The movable lock-up bars 6 and 7 are similarly slotted as shown by the numerals 20 and 21 in Fig. 1. The slots 20 and 21 are substantially the same depth as the slots in the end 3 and the side 5, which hold the plates 18 with the top of the plate 18 in the same plane as the top of the end 3 and the side 5. The slots 20 and 21 are substantially wider than the plates 18, to allow for the endwise movement of the bar 7 and uneven movement of the bar 6 as the type chase is locked-up. A register mark 17 is placed adjacent the innermost end of the plates 18 upon the vertical and horizontal center lines 15 and 16, respectively, and inside of the trim line or groove 10.

Illustrated in Fig. 2, is a register mark 17 which is formed, as by drilling, a flat bottomed circular recess

with a substantially vertical wall 22 and leaving a centrally disposed flat topped upstanding conical core 23 therein. The depth of the register mark in the plate 18 is sufficient to insure a definite impression in the matrix 30 as explained hereinbelow. These register marks 17 are hereinafter referred to as the "center-line" register marks.

After the type chase is made-up, a matrix 30 is molded from the chase in the conventional manner, not shown. The matrix 30 is indicated by the dotted lines in Fig. 1, and the sides 31—32 extend outwardly upon the side 4 and the bar 7 of the type chase 1 a substantial distance to cover the grooves 10 and the register marks 17 on the horizontal center line 16. Similarly the ends 33 and 34 of the matrix 30 extend outwardly upon the top 2 and the bar 6 of the chase 1 covering the grooves 10 and the register marks 17 on the vertical center line 15.

In Fig. 5 is illustrated a matrix 30 having the side which was in contact with the type upward and is thereafter known as the front 35 of the matrix 30. The end 33 becomes the top and the end 34 becomes the bottom of the matrix. The center-line register marks 17 are molded into the matrix 30, as shown in Fig. 5. The register marks 17A are shown on the vertical and horizontal center lines 15 and 16; but it is to be understood that these center line positions, as shown on the matrix 30, are the center lines of the type area 8 from the type chase 1, and are not molded into the matrix 30, and are not necessarily the center lines of the matrix. The matrix 30 is laid upon the made-up type chase 1 in approximately the proper position before molding and therefore the sides and ends of the matrix quite frequently are not parallel with the trim grooves 10. The grooves 10 make a raised line or narrow ridge 10A upon the front 35 of the matrix (Fig. 5) as it is molded from the type chase. These lines 10A are used to trim the sides and ends of the matrix to square-it-up before casting the stereotype plate as hereinafter explained.

As is illustrated in Fig. 6, the center-line register marks 17A, on the matrix 30, are just the reverse of the mark 17 within the surface of the type chase 1, comprising an upstanding flat topped circular projection 36, having a centrally disposed flat bottomed inverted conical recess 37 therein.

The center-line register marks 17A are used for checking the matrices as hereinafter described, but are not properly located for checking the registry of the stereotype printing plates which are made from the register marked matrices. A pair of register marks 40 are placed side by side in the upper surface of the top numbered 2 of the type chase 1, at a selected position adjacent the corners of the type chase area 8. Identical register marks 40 are similarly positioned at the bottom 3 of the type chase 1, in rectangular plates 41 rigidly attached to the bottom 3 by screws 42, by cutting slots in the top of the bottom 3 and the bar 6 as described for the plate 18 hereinabove. Clearly illustrated in Fig. 3, is a typical register mark 40, comprising a flat bottomed conical recess. These register marks 40 are hereinafter referred to as the "corner" register marks.

After the matrix 30 is molded from the make-up type chase 1, the register marks 40 leave a projection 40A adjacent the corners of the matrix 30 within the trim lines 10A, as shown in Fig. 5. These corner register marks 40A on the front 35 of the matrix 30, are the reverse of the marks 40 on the type chase 1. One such mark is illustrated in Fig. 7, comprising an upstanding flat topped conical projection 40A on the matrix 30.

Stereotyping

As the matrices are molded from the type chases, they are sent into the stereotype room where they are placed in an infrared ray heating chamber where each matrix is shrunk. This shrinking of the matrices is for the purpose of making the type impression smaller or narrower,

particularly from side to side of the page to be printed, in order that narrower rolls of paper may be used in the printing operation thus effecting a substantial savings in the amount of paper consumed. Some shrinkage is also present in the top to bottom measurement of the matrix. Approximately one-third of the matrix shrinkage occurs in the first shrinking operation. The matrices do not all shrink evenly nor the same amount due to the variation in the amount of moisture in them and the heat of the shrinking chamber and other factors such as atmospheric conditions, etc.

After this first shrinking operation the matrices are backed or packed, and the top and the right and left sides are trimmed off along the trim lines 10A, formed by the grooves 10. This trimming is done by a conventional paper knife while the matrix is held by the operator guiding the matrix along the path of the knife with one hand while operating the knife with the other hand. The bottom end portion of the matrix is trimmed only slightly in order that the matrix will fit into the final shrinking heat machine. In this final heating for shrinking, where approximately two-thirds of the shrinking takes place, the matrix is held in place by a vacuum pull upon its back side which prevents too fast a shrinkage while approximately 350° F. of heat is applied to the matrix. After this final heat shrinking, the matrix is presumed to be dry and to have shrunk as much as it will. The matrix is then given its final trim along the bottom end 34. Before placing the matrix within the stereotype casting machine, the matrix is again heated to approximately 350° F. for preventing bubbles in the printing plate metal which is normally heated to approximately 600° F. before it contacts the matrix. The stereotype machine cuts or saws the printing plate to the proper width before it is removed from the stereotype machine. If the matrix is not properly seated with one of its sides 31 or 32 in contiguous contact with its slot within the stereotype machine, or if the side placed downward has been trimmed unevenly, or if the top 33 or bottom 34 has not been trimmed in parallel relation, the matrix will have the type impression thus made in "twisted" relation to the longitudinal axis of the casting cylinder of the stereotype machine. This results in a printing plate having a "twisted image" that cannot be registered with its mating colors on the printing press.

The plate is then taken from the stereotype machine and placed within an "auto-miller" machine where the plate is milled from the under side to the desired thickness, and printing press cylinder gripping pockets or grooves are cut in it. This "auto-miller" machine also cools the plate to approximately room temperature. Thereafter the plates are "routed" as may be necessary.

The above description of the stereotyping operation is conventional with most newspaper operations, and is recited here only for the purpose of more clearly relating the present invention to this type of operation.

As a means of comparatively checking the shrinkage of the several matrices used in printing color, a device for registering and holding the matrices while they are trimmed is provided. This registerer and trimmer comprises a box or table-like stand 50 (Fig. 8), having a substantially flat foraminated top 51 connected to a vacuum pump 52 in a conventional manner. The dimensions of the top are equal to the size of the matrix trim lines 10A after the first shrinkage of the matrix 30. The top 51 is equipped with preferably three conventional paper knives 53 for trimming the sides 31 and 32 and the top 33 of the matrix. A substantially flat rectangular plate 55 having substantially smaller proportions than the top 51, is held in fixed spaced superposed central relation to the top 51 by a pair of elongated bracket arms 56 which are attached, as by welding, to one end of the stand 50 and to the upper surface of the plate 55. This plate has side edges 57 and 58 and ends 59 and 60 which are substantially parallel with the side and end edges, respectively, of the top 51. A register indicator 54, comprising a substantially flat rectangular

metal base 61 which is longitudinally slidably disposed upon the vertical and horizontal center line of the plate 55 adjacent each side 57-58 and end 59 and 60, respectively, between a pair of co-operating angle iron guide rails 62 and 63 (Fig. 11), rigidly attached, as by welding, to the upper surface of the plate 55. An elongated register arm 64 is pivotally attached, at a selected point intermediate its ends, to the upper surface of the base 61 between a pair of co-operating upstanding bosses 65 and 66 by a pivot pin 67. The register arm 64 is longitudinally centrally disposed on its respective center line. An elongated conical register pin 70 is rigidly attached at one end to the lower surface of the outermost end 68 of the arm 64, with its small or tapered end 71 downward. The register pin 70 has a length great enough to reach from the horizontal position of the arm 64 to the bottom of the register mark impression 17A in the matrix 30. The circumference of the pin 70 is substantially equal to the diameter of the register mark 17A. A helically wound tension spring 72 is vertically disposed with one end upon the base 61 and its opposite end in contact with the under surface, adjacent the end 69, of the arm 64, to vertically pivot the arm 64 and urge the register pin end 71 into the register mark 17A.

With the knives 53 in a raised position, the matrix 30 is placed flatly upon the top 51 with the front 35 upwardly, and the top 33 at the knife end of the top 51. The register pins 70 are placed within their respective register mark 17A, as shown in Fig. 12. As explained hereinabove, the register arms 64 and bases 61 are longitudinally slidably disposed upon the plate 55 to enable each pin 70 to seat its tip end 71 snugly within the respective register mark 17A. To determine if the matrix has been shrunk evenly, each register base 61 has an index arm 73 pivotally attached to the base 61, adjacent the boss 65, by a pivot pin 74. The index arm 73 is slotted and pivotally attached to the upper surface of the guide rail 62 by a pivot pin 75 therein. Any longitudinal movement of the arm 64 and base 61, as shown by the dotted lines (Fig. 11), is then indicated by the index arm 73 on the indicia 76 placed upon the upper surface of the plate 55 (Fig. 9). If the matrix has been shrunk the proper amount the index arms should read at zero, for example. If the next matrix of the mating color has not shrunk the same amount as the first, then one of the index arms 73 will record the variation on the indicial marking 76. If all matrices checked for a particular color have identical variations, then the printing plates made from them will register. When the matrix has been centrally positioned upon the top 51 the vacuum pump 52 is turned on and exerts a vacuum pull upon the back of the matrix, holding it firmly while the knives 53 are used to trim the sides 31 and 32 and the top 33, along the trim lines 10A. With the vacuum pull upon the matrix 30 through the foraminated top 51 while the sides and top are being trimmed, the matrix 30 cannot move or "creep" thus insuring a true cut along its sides and top. This helps to properly position the matrix within the stereotype casting machine. After the vacuum pump 52 has been turned off, the matrix 30 is removed from the stand 50 and the bottom 34 is trimmed to the approximate proper length as explained hereinabove. It is thought to be evident that the matrices may be comparatively checked for the amount of shrinkage at any stage of their progress through the stereotype operation.

The printing plates 80 (Fig. 13), which are cast from the several matrices 30 and which have been checked for identical shrinkage, will have the register marks 17A cast therein upon the vertical and horizontal center lines of the page to be printed. Similarly the corner register marks 40A on the matrix 30 are cast into the corners of the printing plate 80 and are flat bottomed inverted conical recesses 84 and 85 similar to the register marks 40 of the type chase 1. A printing plate checking device 88 is provided for comparatively checking the accuracy of the plates 80, which includes a horizontally disposed

semi-cylindrical hollow body 90, having its arcuate outer surface facing upwardly and formed to contiguously receive the bearing ribs 81 of the inner surface of a printing plate 80. The body 90 is rigidly mounted on a table 91 or other suitable stand. The plate 80 is placed upon the body 90 (Fig. 14) where it is centrally positioned vertically by a scriber arm 92 adjacent each corner of the body 90, comprising an elongated L-shaped strip metal arm having its longer leg 93 horizontally slidably pivoted at a selected point intermediate its ends to a rigid depending leg 94 of the body 90, by a pin 95 closely received by a longitudinal slot 96 in the leg 93 (Fig. 16). The shorter leg 97 of the scriber arm 92, is vertically disposed and has a length great enough to position its upper or free end portion 98 over the outermost corner register mark 84. A conical register pin 99 is rigidly attached at its base, having its longitudinal axis substantially perpendicular to the inner face of the end portion 98 of the leg 97. The register pins 99 are adapted to seat within the corner register marks 84. The free end of the leg 93 is tapered to a point 100 and is slidably positioned over an index plate 101. A tension spring 102, having its ends attached to the depending leg 94 and the vertical leg 97, respectively, acts to urge the register pin 99 into the register mark 84, as shown by the dotted lines in Fig. 16. When the register pins 99 are not seated within the register marks 84 by reason of the plate 80 not being vertically centered upon the body 90, the deviation from center will be readily discernible by the points 100 of the legs 93 indicating on the index plate 101. The plate 80 may be circularly slid upon the body 90 as, for example, the side 86 of the printing plate 80 may be lowered along one side of the body 90 thus raising the side 83.

When a printing plate 80 has been cast from a matrix which was not properly seated within the stereotype casting box, the image will be "twisted" with relation to the roll of the plate when on the press cylinder. This "twist" will be evident by the position of points 100 on the index plates 101, and no adjusting of the plate 80 upon the body 90 will be able to overcome the "twist"; but being detected at this stage of the process, the plate may be remade.

The printing plate 80 is centrally positioned longitudinally upon the body 90 by vertically disposed scribes 110 adjacent each corner, respectively, of the body 90. Each scribe 110 comprises an elongated metal arm 111 pivotally connected adjacent its lower end, as shown by the dotted lines of Fig. 19, by a pivot pin 113, to a bracket 112 which is rigidly attached to the body 90. An elongated conical register pin 114 is rigidly attached at its base at a selected point on the inner face of the arm 111 in a horizontal position to enter the corner register marks 85. The bracket 112 has a pair of outwardly flared upstanding arms 115 substantially of the same length as the arm 111, and which rigidly holds an indexed plate 116. The upper end of the arm 111 has a tapered portion 117 which indicates upon the index plate 116 the variation from the central position, if any, of the printing plate 80 upon the body 90. The printing plate 80 may be slid longitudinally upon the body 90 to let the tapered ends 117 all read identically upon the index plates 116. The scribe arms 111 are each pivotally hinged at a point adjacent their lower end above the pivot pin 113 as at 118, and as shown in dotted lines (Fig. 20), to allow the upper portion of the arm 111 to be pivoted outwardly from the body 90 while placing the printing plate 80 thereupon. The register pin 114 is held in contact within its respective register mark 85, by a tension spring 119 having its ends attached to the bracket 112 and to the inner face of the arm 111, respectively.

Another purpose of the scribes 92 and 110 is to vertically and longitudinally centrally position the printing plates 80 to drill centering holes in the under side of the printing plates by which the several plates 80 are

identically held while the "auto-miller" cuts printing press "pockets" in the inner side of the plates for the engagement of the gripping fingers on the press cylinders. These centering holes 120 (Fig. 18), are made by two

5 conventional electric drills 121 vertically slidably mounted in a conventional manner on a shaft 122 rigidly attached to the upper surface of the table top 91, centrally positioned within the body 90 and adjacent each end of the same. Each drill 121 has a drill bit 123 therein 10 having a suitable tapered end for drilling a center hole or recess 124 a selected distance into the metal of the printing plate. After the printing plate 80 has been checked for accuracy and centered upon the body 90, the drills are raised by the use of suitable pivoted levers 15 and linkage 124, allowing each drill bit 123 to pass through its co-operating perforation 125 in the body 90, to drill the center holes 120. The upward movement of the drills is regulated by a conventional stop, not shown, to prevent drilling a hole through the printing plate 80.

20 It is believed to be evident that with printing plates 80 which have been comparatively checked for warpage, twisted images, and proper size, have been properly centered upon the checking device 88 and have identically positioned and drilled center holes 120 therein, that 25 co-operating register pins may be placed within the "auto-miller," not shown, to identically hold the several plates 80 of a color series while the "auto-miller" cuts the press cylinder gripping "pockets" in the plate 80. When each printing plate 80 has thus been prepared the 30 plates will need very little, if any, adjustment when placed upon the printing press cylinders.

35 The register marks 84 and 85 have been shown as being depressions within the printing plate. As an alternate embodiment, the register mark might well be made in reverse; that is, a raised projection could be placed upon the top surfaces of the type chase to cause a depression in the matrix which in turn would cast a conical-like register projection 120 upon the printing plate 80, as shown in Fig. 21. A cup-like receiver 122, having 40 a conical bore 123 therein, adapted to receive the register projection 120, is rigidly attached to the scriber arm and operates to register the plate 80 in the same manner as disclosed hereinabove.

45 Obviously the invention is susceptible to some change or alteration without defeating its practicability, and I therefore do not wish to be confined to the preferred embodiment shown in the drawings and described herein, further than I am limited by the scope of the appended claims.

50 I claim:

1. A newspaper type-chase for identically marking the borders of each matrix adjacent the type area of each series of matrices molded therefrom, the frame of said chase having movable lock-up bars and conventional trim line grooves in the upper surface of its ends, sides and lock-up bars, including: a plate rigidly connected to the frame of said chase at one end and one side, respectively, on the respective vertical and horizontal center lines of the type area enclosed by said frame, said plates each overlying the respective adjacent lock-up bars and extending inwardly of the trim line thereon, each said plate having a register mark depression within its upper surface adjacent the inwardly extending end thereof, said register mark depressions disposed upon the respective vertical and horizontal center lines of the type area, causing a series of matrices molded from said chase to have register mark depressions upon the vertical and horizontal center lines of the type area.

2. A newspaper type-chase for identically marking the borders of each matrix adjacent the type area of each 70 of a series of matrices molded therefrom, the frame of said chase having movable lock-up bars and conventional trim line grooves in the upper surface of its ends, sides and lock-up bars, said frame having a register mark depression disposed on the respective vertical and horizontal center lines of the type area enclosed by said frame

in that end and side opposite the respective said lock-up bar, including: a plate rigidly connected to the frame of said chase at one end and one side, respectively, on the respective vertical and horizontal center lines of the type area enclosed by said frame and oppositely disposed from the respective frame register mark depressions, said plates each overlying the respective adjacent lock-up bar, and extending inwardly of the trim line thereon, each said plate having a register mark depression within its upper surface adjacent the inwardly extending end thereof, the register mark depressions of said plates disposed upon the respective vertical and horizontal center lines of the type area, each of said plate register mark depressions comprising a cylindrical recess defining a truncated conical center projecting upwardly from the bottom of the recess, causing a series of matrices inclined from said chase to have inverted truncated conical register mark depressions formed upon the vertical and horizontal center lines of the type area.
